COMBINATION HANDLE AND LIQUID DISPENSER FOR A FLOOR-CONDITIONER

Meyric K. Rogers, La Grange Park, Ill., assignor to Sunbeam Corporation, Chicago, Ill., a corporation of Illinois

Filed Jan. 18, 1967, Ser. No. 5,476

Term of patent 14 years

(Cl. D37—3)

FIG. 1 is a perspective view of a combination handle and liquid dispenser for a floor conditioner, showing my new design;

FIG. 2 is an enlarged front elevational view thereof;

FIG. 3 is a sectional view taken along the section line 3—3 of FIG. 2;

FIG. 4 is a rear elevational view thereof; and

FIG. 5 is a side elevational view thereof.

The broken lines shown in FIGS. 1, 4 and 5 are for illustrative purpose only.

I claim:

The ornamental design for a combination handle and liquid dispenser for a floor conditioner, as shown and described.
